7 Claims. (Cl. 230—125)

The present invention relates to fans.

The present application is a division of my copending application Serial No. 493,432, filed March 1, 1955, and entitled "Fans."

In general there are two classical types of well known fans, namely, the axial flow type of fan and the radial flow type of fan. Both of these known types of fans have disadvantages. Thus, these known fans invariably make a great amount of noise during their operation, and considerable problems are involved in locating such fans in small spaces. Furthermore, it is difficult without replacing one of these known fans to provide great variations in the output.

One of the objects of the present invention is to overcome the above drawbacks by providing a fan which will operate with far less noise than the above-discussed conventional fans, will provide a higher output than the known fans for a given size and speed of rotation of the fans, and will be capable of providing a wide range in output simply by changing the speed of rotation of the fan.

Another object of the present invention is to provide a fan which, except for the motor which drives the same, may be entirely located within a duct so that a minimum of space is required for the fan of the invention.

An additional object of the present invention is to provide a fan construction which may be very easily adapted to any given conditions.

With the above objects in view the present invention mainly consists of a fan comprising impeller means which includes a plurality of elongated impeller blades of substantially the same lengths uniformly distributed about a cylindrical space and respectively having inner side edges located along a first cylinder and outer side edges located along a second cylinder coaxial with and greater than the first cylinder, these blades being substantially parallel to the common axis of the cylinders. A casing means supports the impeller means for rotation about this common axis, and this casing means is formed with an inlet communicating at any given instant with a first plurality of blades located on one side of the above-mentioned axis and with an outlet communicating at a given instant with a second plurality of blades located at the opposite side of this axis. The inlet extends through a first angle about this axis, whereas the outlet extends through a second angle smaller than this first angle about the axis. Guide means supported by these casing means are also provided, which guide means are located within the space about which the impeller blades are uniformly distributed and the guide means serve to guide the fluid across this space from the first to the second plurality of blades.

The novel features which are considered as characteristic for the invention are set forth in particular in the appended claims. The invention itself, however, both as to its construction and its method of operation, together with additional objects and advantages thereof,

2

will be best understood from the following description of specific embodiments when read in connection with the accompanying drawings, in which:

Fig. 1 is a sectional side elevational view of a fan constructed in accordance with the present invention;

Fig. 2 is a fragmentary view corresponding to Fig. 1 of part of the fan of Fig. 1 with a different structure located within the fan; and

Fig. 3 is a fragmentary sectional view taken along the line 3—3 of Fig. 1 in the direction of the arrows.

Before proceeding to a detailed discussion of the drawings shown in this application, it is pointed out that the fan of the present invention differs basically from known fans in that it cannot be classified either as a radial flow fan or as an axial flow fan. According to the present invention air is sucked into the fan of the invention through the spaces between some of the impeller blades of the fan and this air (or other fluid) passes across the interior of the fan and moves out through the spaces between some of the impeller blades, at a particular instant. Thus, with the fan of the present invention the fluid flows twice through the blades of the impeller.

Referring now to the drawings, Fig. 1 shows an impeller 1 provided with impeller blades distributed along a cylinder, as is evident from Fig. 1, the impeller 1 turning in a clockwise direction, as viewed in Fig. 1, and as indicated by the arrow of Fig. 1. The impeller blades of the impeller 1 are uniformly distributed about a cylindrical space 2 and have respectively inner side edges located along a first cylinder and outer side edges located along a second cylinder coaxial with and having a diameter greater than the first cylinder and these blades are substantially parallel to the common axis of the cylinders. Located within the cylindrical space 2 are guide bodies 3 and 4 and a plurality of guide vanes 3'. The guide bodies 3 and 4 have each an outer surface substantially parallel to the first cylinder along which the inner side edges of the impeller blades are located and this outer surface is spaced from the first cylinder a small distance. The impeller is supported for rotation by a casing which is formed with an inlet 5 and an outlet 6, and it will be noted that the inlet angle extending from point 7 to point 8 indicated in Fig. 1 is greater than the outlet angle extending from point 9 to point 10 indicated in Fig. 1. Fig. 3 shows the manner in which the impeller and guides 3 and 4 are mounted on the casing 15. Thus, this casing 15 includes side walls 16 and 17, and the guides 3 and 4, as well as the several guides shown in Fig. 1 between the guides 3 and 4, extend between and are fixed to a pair of end plates 18 and 19. The end plate 18 is fixed to a pair of studs 20 which extend to and are fixed to the side wall 17, and the end plate 19 is located within the impeller 1. This impeller 1 is coaxial with the cylinder in which the guides are located, and the blades of the impeller are carried by a pair of rings 21 and 22 which are slidable on the peripheries of the end plates 19 and 18, respectively, so that these end plates form bearings for the impeller. The ring 21 is in the form of an annular flange integral with a plate 23 fixed to a shaft 24 which extends through side wall 16 of the casing 15 and which is turnably supported by the side wall, a pulley 25 or the like being fixed to the shaft 24 so that in this way impeller 1 may be driven.

In operation, as the impeller 1 turns in a clockwise direction, as viewed in Fig. 1, the blades of the impeller suck air in through the inlet 5, force this air along the space 2 where the guides for the air are located, and the air is forced again through the impeller blades out through the outlet 6. It will be noted that the angle of the inlet 5 about the axis of rotation of the impeller is greater than that of the outlet 6.

Fig. 2 shows a fan identical with that of Fig. 1 except that the interior of the space surrounded by the impeller is provided with a guide body 3 of the same configuration as the guide body shown in Fig. 1 and in addition thereto with a single guide body 10 and a plurality of short stationary vanes 11. The guide body 10 has an outer surface located on the same cylindrical surface as the outer surface of the guide body 3, but guide body 10 has a bulbous shape extending considerably into the cylindrical space 2. The short guide vanes 11 are located opposite the outlet 6 shown in Fig. 1. Guide bodies 3 and 10 in combination with the short guide vanes 11 operate in the same way as the guides of Fig. 1 to direct the air across the space surrounded by the impeller.

It has been found that the fan of the invention, which may be called a cross flow fan, produces far less noise at a given speed of rotation than either a radial or axial flow conventional fan operating at the same speed of rotation. Furthermore, it will be noted that the fan of the invention may have its impeller located directly within a duct, so that very little space is required for the fan of the invention. The impeller may be made of any desired length, since the length of the impeller in no way influences the operation of the fan of the invention, it is only necessary to change the speed of rotation of the impeller accordingly. Furthermore, with the fan of the invention there are no operating characteristics which change suddenly at two speeds of operation which are close to each other. In other words, when increasing or decreasing the speed of rotation of the fan of the invention there is no danger of passing through certain critical speeds as is the case with known fans.

While the invention has been illustrated and described as embodied in cross flow fans, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a casing, a fan comprising, in combination, a disc, mean supporting said disc in said casing for rotation about an axis in a predetermined direction, impeller means including a plurality of elongated impeller blades each connected at one end to said disc uniformly distributed around the axis of rotation thereof at the same distance from such axis and each being substantially parallel to the axis to form a cylindrical space, said casing being formed with an inlet passage facing a first plurality of blades located on one side of said axis and with an outlet passage facing a second plurality of blades at the opposite side of said axis, said casing having two wall parts of differing length adjacent the outer peripheries of the blades separating the inlet and outlet, whereby a fluid moved by said impeller through said casing flows through said inlet and the spaces between said first plurality of impeller blades across the cylindrical space within the

blades and through said second plurality of impeller blades to said outlet; and stationary guide means supported by said casing and located within said space for guiding a fluid across said space from said first to said

5 second plurality of blades, said guide means lying on both sides of a line joining the axes of the inlet and outlet passages, said guide means guiding the fluid at the outlet side of the cylindrical space in a direction forming an acute angle with the periphery of the impeller means 10 and sloping in a direction opposite to said predetermined direction of rotation, said blades forming the outermost member of the fan, the blades on the side of the inlet passage receiving intake fluid directly from the inlet and feeding it into said cylindrical space, and the blades 15 on the outlet side receiving fluid from said cylindrical space and forcing it directly into the outlet, said inlet extending through a first angle about said axis and said outlet extending through a second angle about said axis smaller than said first angle.

20 2. In a fan as claimed in claim 1, said inlet and outlet each having a substantially rectangular cross-section and each having a width substantially equal to the length of said blades.

25 3. In a fan as claimed in claim 1, said guide means comprising a plurality of guide vanes located in said cylindrical space.

4. In a fan as claimed in claim 1, said guide means comprising a plurality of guide vanes located in said cylindrical space and extending between said inlet and 30 said outlet.

5. In a fan as claimed in claim 1, said guide means comprising a plurality of guide vanes located in said cylindrical space, and at least one guide body having an outer surface portion substantially parallel to the inner edges of the blades and spaced a small distance therefrom.

40 6. In a fan as claimed in claim 1, said guide means comprising a plurality of guide vanes located in said cylindrical space, a first guide body having an outer surface portion substantially parallel to the outer edges of said blades and spaced a small distance therefrom, and a second guide body having an outer surface portion substantially parallel to the outer edges of said blades and spaced a small distance therefrom, said second guide body extending a considerable distance toward said first guide body into said cylindrical space.

45 7. In a fan as claimed in claim 1, said guide means comprising a first guide body having an outer surface portion substantially parallel to the outer edges of said blades and spaced a small distance therefrom, a second guide body having an outer surface portion substantially parallel and spaced a small distance therefrom, said second guide body extending a considerable distance toward said first guide body into said cylindrical space, and a plurality of short guide vanes located in said cylindrical space between said first and said second guide bodies and adjacent to the outlet.
